UNITED STATES PATENT OFFICE.

ROY L. BURD, OF DETROIT, MICHIGAN, ASSIGNOR TO BURROUGHS ADDING MACHINE COMPANY, OF DETROIT, MICHIGAN, A CORPORATION OF MICHIGAN.

ADDING-MACHINE.

936,087.

Specification of Letters Patent.

Patented Oct. 5, 1909.

Application filed April 18, 1908. Serial No. 427,891.

To all whom it may concern:

Be it known that I, ROY L. BURD, a citizen of the United States, residing at Detroit, Wayne county, Michigan, have invented certain new and useful Improvements in Adding-Machines, of which the following is a specification.

This invention relates more particularly to that type of adding and listing machine in which provision is made for what is called "splitting," meaning that the usual coöperative action of the impression devices for the automatic filling in of ciphers is suspended at a predetermined point so that two distinct columns of imprints can be run, one made up of designating numbers, for instance, and the other of amounts. It frequently happens that when using an adding and listing machine in this way the designating numbers run consecutively and where they extend as high as tens or hundreds or higher the same numeral keys would have to be repeatedly depressed, it being understood of course that with each operation of the machine an automatic restoration of depressed numeral keys takes place. It will further be understood that it is customary in machines of this general character to employ a special key usually called a "repeat" key which does away with the necessity of repeatedly depressing the same amount keys where the same amount is to be added and printed in successive operations of the machine. This well known special key does not however, provide for such a contingency as that above mentioned, where the machine is split and higher order numerals of designating numbers would be the same in successive operations of the machine.

The principal object of the present invention is to provide for avoiding the necessity of repeatedly depressing the same numeral keys for designating numbers where such numbers run consecutively, and so provision is made for disconnecting the releasing or restoring devices for certain of the rows or sets of keys so that although depressed keys which represent amounts will be released as usual, keys used for designating numbers will not be released or restored automatically in an operation of the machine. Furthermore the usual automatic release operation

will include the row or set of keys which will be used for the units numeral of any designating number. For example, if 55 vouchers were being listed in their numerical order with the amounts of the vouchers in a parallel vertical column, the machine would operate under a split adjustment providing for enough rows of keys to accommodate the highest designating number being usable separately from the balance of the rows of keys which would be used to represent amounts, and the impression devices corresponding with the first-mentioned 65 division of keys being coöperatively related for cipher printing but not coöperating for such purpose with the impression devices associated with the balance of the rows of keys. However, the disconnecting point in 70 the key releasing or restoring mechanism would be located one step or decimal place to the left of that where the disconnection in the impression devices occurs. Starting then with say voucher No. 1240, the 1, 2 and 75 4 keys would remain depressed until voucher No. 1250 was reached, the automatic restoring or releasing mechanism not taking effect upon the keys of the rows in which said 1, 2 and 4 keys would remain depressed, though 80 it would take effect upon the remaining row of keys in which the units numeral of the designating number would be depressed. It follows that under such an arrangement, instead of having to repeatedly depress the 85 1, 2 and 4 keys, the operator would simply have to depress those keys once and then operate the machine ten times, changing the units numeral each time, and if the listing continued beyond this it would not be 90 necessary to release all of the depressed keys before the usual column release key could be manipulated to release the 4 key, thereupon depressing the 5 key and proceeding as before.

Of the accompanying drawings forming part of this specification, Figure 1 represents in right side elevation the interior parts of an adding and listing machine of the well known Burroughs type, the invention in the present instance being shown as adapted to that particular type of machine; Fig. 2 represents on an enlarged scale a portion of the key releasing mechanism in rear

elevation with some parts broken to economize space; Fig. 3 represents a partial left side elevation of the machine with some parts in section and under what may be termed a normal adjustment, meaning one in which there is no disconnection in the releasing or restoring mechanism; Figs. 4 and 5 are elevations somewhat similar to Fig. 3, though not showing so much of the machine and illustrating the other adjustment when the releasing mechanism is disconnected between its two sections; Fig. 6 is a partial left side elevation of the machine very similar to Fig. 3 but extending to the impression devices; Fig. 7 is a sectional plan view taken on the line 7—7 of Fig. 6; and Fig. 8 is a section taken on the line 8—8 of Fig. 6.

As above indicated, the invention is here shown applied to the well known Burroughs adding and listing machine and reference may be had to the William S. Burroughs patents Nos. 504,963 and 505,798 issued September 12, 1903, for an understanding of the general principles of such a machine. It will not be necessary to enumerate all of the familiar parts of this machine, though some of them will be specially designated on account of intimate association with the new parts introduced for carrying out the present invention.

Referring first to Fig. 1, the numeral 300 designates the usual main driving shaft to which a handle is detachably applied, said shaft carrying the full stroke sector 311 and the latter having a shoulder which engages the downwardly extending arm 622 of a bell crank lever loosely mounted upon the central rock shaft 600 and having a rearwardly extending arm 630 carrying a pivoted wipe plate or pawl 623 held by a spring 618 in contact with the projection *a* of said arm 620, said spring not only tending to hold the plate against said projection but also acting to lower said arm 630 and press the depending arm 622 against the shoulder of the full stroke sector 311. Said wipe plate normally stands just above a roller 262 on the depending portion of the right hand side piece 219 of the usual key releasing and restoring bail, which comprises a rock shaft 207 and a rod 202. This rod acts upon detents 228 which engage openings in sliding strips or bars 214, there being one of the latter for each row of amount keys 291. Depression of a key operates as usual to thrust the associated strip 214 rearwardly against spring pressure and engage it with the detent 228. The automatic release takes place by reason of the wipe plate 623 having passed below the roller 262 during the forward stroke of the operating handle and in the return stroke of said handle operating upon said roller to swing the bail forward.

The bail may be swung independently of this wipe plate by depressing a special key *C* which is ordinarily termed the error or correction key and surmounts the upper end of a bell crank lever 227 suitably linked to the bail. Provision is also made as usual for separately releasing a depressed key in a single bank. Thus, a series of keys *R* are arranged along the top of the keyboard to act upon small levers *r*, one for each of the detents 228. The keys *R* are upheld by springs with sufficient clearance between them and the small levers to provide for the necessary play of the detents 228.

All of the above enumerated parts are familiar in the regular Burroughs adding and listing machine. In carrying out the present invention the key releasing bail proper does not extend entirely across the machine, but, as illustrated in Fig. 2, terminates at an intermediate point in a side piece 219^a, though the shaft 207 extends entirely across the machine. A separate and supplemental bail is employed, comprising a right hand side piece 219^b, a cross rod 202^a and a left hand side piece 219^c; also a sleeve 207^a which surrounds the rock shaft 207. There is secured to the latter at the left beyond said sleeve an arm *B* which projects upwardly and rearwardly and has pivotally mounted upon its upper extremity a forked latch piece *D* whose upper branch is notched as at *d* to embrace the stud *d'* on an upward projection of the left hand side piece 219^c of the supplemental bail. The lower branch of said latch piece is connected by a spring 100 *e* with the arm *B* to enforce engagement between said notch and the pin or stud *d'*. It will be obvious that so long as this engagement continues the two bails will operate as one and perform exactly the same as 105 the usual single structure of the regular machine. However, if the latch piece is lifted so as to uncouple the bails, then of course only the bail proper or the right hand section of the bail structure will be vibrated 110 by the wipe plate 623 and the usual spring 288 which retracts the bail. For the purpose of uncoupling the bail sections a key *S* is employed, the same arranged to slide through the keyboard plates, its stem *s* being 115 notched as at *s'* to engage under the upper plate when the key is depressed, thus providing for its remaining indefinitely depressed. The lower end of the key stem is jointed to the forward end of a lever *S'* 120 pivoted intermediate its ends upon a stud *s*² and jointed at its rear end to an upstanding bar *S*², the latter slotted to slide upon the shaft 207 and formed above said shaft with a broadened portion *s*³ immediately below a 125 roller *d*² on the lower branch of the latch piece *D*. It will be seen that depression of the key *S* elevates the bar *S*² through the

medium of the lever S' and the action of the broadened upper part of said bar upon the roller d^2 lifts the latch piece and thereby uncouples the two sections of the bail. The 5 adjustment under such conditions is illustrated in Figs. 4 and 5. In Fig. 4 the parts are shown relatively positioned as they would be prior to the operation of the machine, whereas in Fig. 5 the same parts are 10 illustrated relatively positioned as they would be when the handle has not quite returned home. It will be noted that the broadened upper end of the bar S^2 provides for the travel of the roller d^2 to and fro as 15 the bail proper or the right hand section of the bail structure vibrates, while the left hand section remains at normal position.

It will be obvious that the above described construction provides for keys remaining 20 pressed in rows of keys whose detents co-operate with the left hand section of the releasing bail. Therefore by simply depressing the key S when the machine is 25 operating under a split adjustment work such as that hereinbefore mentioned can be carried on without requiring repeated depression of the same numeral keys for designating serial numbers as of vouchers.

In Figs. 6 and 7 there is illustrated a 30 known form of mechanism for accomplishing the so-called split and for the details of this mechanism reference may be had to Patent No. 825,205, issued July 3, 1906, on the invention of C. W. Gooch. The numeral 35 715 designates the usual printing hammer which is operated by the lever 716, the latter being restrained by a latch 717 which is lifted by a pawl 718. As here shown the fifth latch from the left, see Fig. 7, is made 40 without the usual overlapping tail α . The tripping at this point for cipher printing purposes is effected through the medium of a coupler A which slides and pivots on a shaft 706 and is equipped with pins a^2 and 45 a^3 engaging the tailless latch and the next adjacent latch to the right. This coupler is under the control of a bail A' and the latter is in turn under control of a key A^2 , all as fully explained in the said Gooch 50 patent. The particular character of the mechanism for effecting the split is of no particular importance in connection with the present invention, but as the latter is of special advantage in a so-called split and 55 normal machine reference is made as above to the Gooch construction which provides for establishing a split at will. It will have been noted that the split occurs between the fifth and sixth hammer latches, counting 60 from the left, which means that five rows of keys can be used for setting up designating numbers. Under such conditions the left hand bail section should co-operate with the detents of the four left hand rows of keys.

Although the fifth row of keys beginning 65 from the left belongs to the designating number division of the machine, yet its detent should be tripped in each operation because that row of keys is used for the unit numeral, which would of course change with 70 each operation of the machine. Fig. 8 illustrates the location of the point of disconnection in the bail structure as related to the rows of keys.

While the above described construction is 75 believed to be especially well adapted to carry out the object of the invention, it is to be understood that the invention is not limited to that particular construction, nor to the particular type of adding and listing 80 machine to which it is here shown adapted.

What is claimed is:

1. In a machine of the character described, the combination of rows of depressible keys, means for automatically restoring depressed 85 keys of all rows simultaneously, said means being of sectional character, and manipulative means for uncoupling the sections to permit a key of one or more rows remaining depressed during successive operations of the 90 machine while keys of other rows are restored.

2. In a machine of the character described, the combination of rows of depressible keys, means for automatically restoring depressed 95 keys of all rows simultaneously, said means being of sectional character, manipulative means for uncoupling the sections to permit a key of one or more rows remaining depressed during successive operations of the 100 machine while keys of other rows are restored, and printing devices co-operatively related for the filling in of ciphers, with provisions for interrupting the co-operative action at will between the printing device next 105 beyond that which corresponds with the row of keys where automatic restoration is suspended and the next adjacent printing device to the right.

3. In a machine of the character described, 110 the combination of rows of depressible amount keys, a sectional restoring bail, means for vibrating the same, and means for disconnecting its sections.

4. In a machine of the character described, 115 the combination of rows of depressible amount keys, a sectional restoring bail, a movable coupling between the sections, vibrating means applied to one section, and manipulative means for displacing the coupling to prevent vibration of the other section. 120

5. In a machine of the character described, 125 the combination of rows of depressible amount keys, a sectional restoring bail, a latch normally connecting the two sections of the bail, a latch lifting bar, a key, and operating connections between the same and said bar.

6. In a machine of the character described, the combination of rows of depressible amount keys, a sectional restoring bail, a pivoted spring-held latch connecting the sections of the bail and having a roller, a latch-lifting bar engaging under said roller which in the vibration of the bail traverses the upper edge of said bar, a lever connected to the latter, and a depressible key connected to the lever.
